UNITED STATES PATENT OFFICE

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA

COMPRESSING UNIT FOR INFLAMMABLE GAS

Application filed December 13, 1928. Serial No. 325,747.

This invention relates to a gas compressing apparatus and more particularly to an apparatus of this type for compressing an inflammable gas such as illuminating gas for use in oxygen-illuminating gas cutting and welding.

Illuminating gas as generally supplied in gas mains is under a relatively low pressure so that it is not directly usable in a welding torch. Accordingly it is necessary to use a compressing apparatus, preferably portable, to raise its pressure to a suitable degree to obtain rapid flow and consequent intensity of flame.

Heretofore it has been customary to use a reciprocating compressor to force the gas into a large reservoir which serves to smooth out the pulsations so that a substantially uniform flow to the burner is obtainable. Because of the large size of reservoir necessary to insure such uniform flow it is not feasible to recover the lubricant carried into the reservoir by the compressed gas and it is customary to waste this lubricant, drawing it off from time to time from the bottom of the reservoir.

In apparatus of this type commonly used, another source of lubricant waste occurs due to the carrying over in the form of a fine mist of lubricant in the compressed gas. The particles of lubricant in this mist do not completely coalesce in the reservoir and hence are carried over into the torch where the high temperature causes carbonization resulting in clogging of the small passages therein.

In order to obtain any practical degree of coalescence whatever, it is necessary to use an excessively large reservoir in which the velocity of the gas is reduced almost to zero.

It is an object of the present invention to provide a compressing apparatus of the character described in which a small reservoir may be used permitting the recovering of lubricant thus minimizing waste and providing thorough sealing of the pump. A further object consists of the provision of means for properly separating the lubricant from the compressed gas to prevent its passage to the torch and to permit the use of a small reservoir.

In the drawing there is illustrated in perspective a compressing unit embodying the invention.

The unit, which is portable and which may be mounted on wheels or a truck, comprises a chassis 2 consisting of a platform supported on legs and provided with handles 4 which provide for ready handling. Mounted on the chassis is a suitable motor 6, controlled through an enclosed switch 8, which motor drives a rotary compressor 10 through a belt 12 trained about pulleys on the motor and compressor shafts. The rotary compressor is preferably of the type having blades slideable through the axis of rotation contacting with the interior of an eccentric casing and receiving and delivering the gas through ports in the periphery of the casing. It may, for example, be of the construction shown in the application of Eugene L. Barnes, Serial No. 32,174, filed May 22, 1925, which has resulted in Patent No. 1,696,564, issued December 25, 1928, in which type of compressor lubricant is fed to the rotating parts through the bearing and shaft.

The compressor receives gas from a main through either a flexible or rigid tube 14, and delivers the compressed gas at 16 to a separator coil 18, preferably wound about a horizontal axis, which coil discharges into the reservoir consisting of a tank 20 secured to the chassis by suitable straps.

A discharge pipe 22 communicates with the top of the reservoir and is arranged to be connected as by means of a flexible tube 24, with one or a plurality of torches T.

The lubricant inlet at the bearing of the compressor is connected to a tube 26 which passes into tank 20 and opens beneath a normal lubricant level therein. The compressed gas in the tank above the lubricant then serves to force the lubricant into the compressor.

A by-pass pipe line 28 connects the intake and discharge of the pump, a suitable relief valve 30 being interposed in this line to relieve pressure in the reservoir if it becomes excessive, due, for example, to the lack of use of the torch or torches when the motor is running. The connection from the relief

valve to the intake prevents the discharge of the inflammable gas into the atmosphere.

A gauge 32 may be provided to indicate the pressure in the reservoir.

5 The spiral separator 18 imparts a rapid rotary movement to the compressed gas carrying entrained lubricant, the heavy lubricant being coalesced on the walls of the tube by centrifugal action. It is found preferable 10 to arrange the spiral with its axis horizontal since it appears that lubricant collecting in the lower portions of the turns serves to scrub the gas and remove the mist more thoroughly therefrom.

15 By reason of the high speed of operation and consequent rapidity of sequence of pulsations due to the use of a rotary compressor, the pulsations may be smoothed out to obtain an even pressure at the torch by the use 20 of a much smaller reservoir than that required when a reciprocating pump is used. Tank 20 may, therefore, serve not only as a gas reservoir but also as a lubricant reservoir from which the lubricant is supplied to the 25 compressor by the pressure of the gas therein. Separator 18 also tends to make possible the use of a small reservoir by thoroughly breaking up the mist of lubricant in the compressed gas so that the larger particles resulting from coalescence will settle in the small tank even though the gas velocity therein is not reduced to substantially zero. Accordingly it will be seen that the various 30 parts cooperate to minimize the size of reservoir required and thus, by permitting a circulation of lubricant, serve to economize on lubricant and permit its use in sufficient quantities to insure effective sealing of the compressor. Furthermore the objectionable 35 clogging of the torch is avoided.

40 What I claim and desire to protect by Letters Patent is:

45 1. In combination with a burner, a unit for compressing inflammable gas including a compressor, a reservoir, a lubricant separator consisting of a spiral tube through which compressed gas passes from the compressor to the reservoir, and a conduit for leading compressed gas from the reservoir to the burner.

50 2. In combination with a burner, a unit for compressing inflammable gas including a compressor, a reservoir, a lubricant separator consisting of a spiral tube having its axis substantially horizontal through which compressed gas passes from the compressor to the reservoir, and a conduit for leading compressed gas from the reservoir to the burner.

55 3. In combination with a burner, a unit for compressing inflammable gas including a compressor, a reservoir, a lubricant separator consisting of a spiral tube through which compressed gas passes from the compressor to the reservoir, a conduit for leading lubricant from the reservoir back to the com-

pressor, and a conduit for leading compressed gas from the reservoir to the burner.

4. In combination with a burner, a unit for compressing inflammable gas including a rotary compressor, a reservoir, a lubricant separator consisting of a spiral tube through which compressed gas passes from the compressor to the reservoir, a conduit for leading lubricant from the reservoir back to the compressor, and a conduit for leading compressed gas from the reservoir to the burner.

In testimony of which invention, I have hereunto set my hand at Philadelphia, Pa., on this tenth day of December, 1928.

FRANK A. BROWNE.
